ROTARY KILN FOR BURNING CEMENT, MAGNESITE, LIME, AND THE LIKE

Filed July 3, 1925

Inventor,
Harry Stehmann,
By Henry M. M. atty.

UNITED STATES PATENT OFFICE.

HARRY STEHMANN, OF BERLIN-HOHENSCHONHAUSEN, GERMANY.

ROTARY KILN FOR BURNING CEMENT, MAGNESITE, LIME, AND THE LIKE.

Application filed July 3, 1925, Serial No. 41,408, and in Germany May 20, 1922.

When rotary kilns are used for burning cement, magnesite, lime and the like, too much air, not required for the burning process, is admitted into the rotary kiln through 5 the discharge slot for the finished material whereby the economy of the burning is unfavourably influenced as the consumption of coal is increased.

This invention has for its object to avoid 10 this inconvenience by intimately connecting with the revolving tubular kiln a device which ensures that, in totally or partially neglecting the recuperation of the heat radiating from the material which has been 15 burned, only the accurately regulated quantity of air is supplied to the rotary kiln which is actually required for the burning process.

It has been found that heat-economical advantages may be obtained even without recuperation of the heat of the burnt material when the discharge of the rotary kiln is closed absolutely airtight and the kiln is worked with the smallest possible quantity 25 of air regulated in accordance with the material to be burned. The new working method may be applied to any kind of rotary kilns even if, owing to insufficient building height, it should be impossible to insert a 30 cooling chamber. The invention is based on these considerations as, according to the invention, the less important advantage of the recuperation of the heat radiating from the material which has been burned is entirely 35 or partly abandoned and the more important heat-economical advantage is utilized which results from the working with accurately regulated minimum quantities of air for the minimum quantities of fuel required 40 for the material to be burned, any prejudicial excess of air being avoided.

The rotary kiln is equipped, according to the invention with an airtightly-closing discharging device adapted to permit accurate adjustment of the rotary kiln for the admission 45 of the actually required minimum quantity of air corresponding to the minimum quantity of fuel. The usual means may be provided eventually for the artificial cooling 50 of the discharging device the required

minimum quantity of combustion air being admitted into the rotary kiln above said discharging device.

An embodiment of the invention is illustrated, by way of example, in the accompanying drawing which shows an improved rotary kiln in longitudinal section.

The rotary kiln *a* terminates at the discharge end in a head piece *b* which serves for closing and with which the airtightly closing discharging device *c* is connected, the latter of which may be cooled by air or water in any well known manner. The combustion air is admitted above the discharging device into the rotary kiln together with the fuel through the pipe *d* and the pipe *e* is used to introduce additional air which serves to regulate the air admission to the minimum quantity required. It will be noted that the pipe *e* discharges into the head *b* which has an air-tight connection with the kiln *a* above the discharge devices *c*, but below the discharge or lower end of the rotary portion *a* of the kiln. This air is heated by the cement clinker as it falls to the devices *c* which, as previously described, prevent the passage of a current of air up through them when they are opened to discharge their contents. The air for both the fuel feeding and the auxiliary combustion air is supplied by blowers or fans *f*.

I claim:

A rotary kiln for burning cement, magnesite and lime, including a rotary inclined body portion, a head at the lower end thereof, an air-tight discharge device directly connected to the lower end of said head and means to admit fuel to said head and body portion, in combination with an air supply pipe arranged in the head to direct a current of air against the hot material discharging from the lower end of the kiln, said discharge device including two interconnected cooperating discharge valves spaced apart to prevent ingress of air during the discharge of the material.

In testimony that I claim the foregoing as my invention, I have signed my name.

HARRY STEHMANN.
